Filed Oct. 26, 1970, Ser. No. 25,659

Term of patent 14 years

Int. Cl. D14—02

U.S. Cl. D26—5 C

FIG. 1

FIG. 2

FIG. 3

FIG. 1 is a front perspective view of a cabinet for data processing equipment showing our design;

FIG. 2 is a rear perspective view thereof; and

FIG. 3 is a modified form of the cabinet of FIG. 1.

The control panel shown generally in FIG. 3 has substantially the same appearance as the control panel shown in greater detail in FIG. 1.

The rear of FIG. 3 is the same as FIG. 2 except it includes the additional top enclosure which appears from the rear the same as from the front.

We claim:

The ornamental design of a cabinet for data processing equipment, substantially as shown and described.
